UNITED STATES PATENT OFFICE.

JOHN G. W. ROMANS, OF BRAINTREE, MASSACHUSETTS, ASSIGNOR, BY MESNE ASSIGNMENTS, TO NANCY A. ROMANS, OF BRAINTREE, MASSACHUSETTS.

REGISTERING MECHANISM.

SPECIFICATION forming part of Letters Patent No. 760,487, dated May 24, 1904.

Application filed October 30, 1902. Serial No. 129,438. (No model.)

To all whom it may concern:

Be it known that I, JOHN G. W. ROMANS, a citizen of the United States, residing in Braintree, in the county of Norfolk and State of Massachusetts, have invented certain new and useful Improvements in Registering Mechanism, of which the following is a specification.

The objects of my invention are as follows:

One object of my invention is to produce a registering device having a small number of parts, simple in construction, and not liable to get out of order.

Another object of my invention is to so arrange the parts of the mechanism that the registering means will be stationary after registering until the several parts are returned to their normal zero position.

A further object of my invention is to so construct the different parts as to relieve the registering portions from the shock and jar incident to use.

Another object of my invention is to so construct the registering device that it will be independent of the operating device when the two are in certain relative positions.

In the drawings accompanying this specification and forming a part thereof, Figure 1 represents a front elevation of the registering device with the operating parts in normal or zero position. Fig. 2 is a side elevation of the same, with portions of the frame broken away. Fig. 3 is a cross-section through line 3-3 of Fig. 1 looking downward. Fig. 4 is a rear elevation with a portion of the frame-work cut away, showing the operating and registering slides in normal or zero position. Fig. 5 is a rear elevation with part of the frame broken away to show the slides in position to register. Fig. 6 is a rear elevation with portions of the frame broken away to show the slides about to return to their normal or zero position. Fig. 7 is a side elevation of the operating-slide. Fig. 8 is an edge elevation of same. Fig. 9 is a front elevation of one form of indicator-dial and pointer that may be used with the device. Fig. 10 is an edge elevation of same.

In the drawings, which represent the best form now known to me for constructing my device, A and A' represent the front and rear

plates in which the different parts of my mechanism are mounted.

B represents posts used to tie the front and rear frame-plates together.

In illustrating one of the uses to which my registering device may be put I have represented it as used with a weighing-scale, and D represents a plunger attached by a bracket to the spring-rods of a weighing-scale platform. The plunger D is adapted to contact 55 with the operating-slide E, which forms the operative portion of my registering device. The operating-slide E has attached to it the portion E', having on one of its edges the ratchet-teeth E'', the use of which will be here- 60 inafter explained.

In using my registering device with a weighing-scale or other mechanisms of the kind I use a coin-releasing lever, as F, which is pivoted to the frame of the machine by 70 means of the cone-pointed pivot-points F² F³. The outer end of the coin-lever F is provided with a coin-receptacle F'. The inner end of the coin-lever is provided with the counterbalance F³ and the pawl F', attached to an upwardly-extending portion to the lever F, which engages the ratchet-wheel F⁵, attached to the escapement-wheel G, which is mounted on the shaft F⁷. The escapement-wheel G is controlled by the escapement G', mounted on 75 the shaft G', which in turn is pivoted to the frame by the cone-pointed trunnions G² G³. There is also attached to the shaft G' the balance-wheel G⁴, which serves to regulate the movement of the escapement G'. 80

The slide E has a free longitudinal movement in the brackets A² and A³, attached to the frame-plate A'. There are also attached to brackets A² and A³ the pins H and H', which serve as a guide for the registering-slide I, 90 which registering-slide is provided with ratchet-teeth on one of its edges, the purpose of which will be hereinafter explained. The slide I is also provided with a rack portion J, adapted to receive the teeth of the gear K, mounted on the shaft K', and is for the purpose of imparting a rotary movement to said shaft K'. A stud L (see Fig. 2) is attached to the frame-plate A' and has mounted thereon ratchet-pawls L' and L'', the ratchet- 95 too

pawl L' being adapted to engage with the ratchet-teeth on the edge of the portion E' , while the ratchet-pawl L^2 engages with the ratchet-teeth on the registering-slide I . A lug I' is attached to the lower part of the registering-slide I and is adapted to engage with the lower end of the operating-slide portion E' , so that when said operating-slide E' is moved downward it will carry with it the slide I and in turn rotate the shaft K' . Mounted on the stud L are the springs L^3 and L^4 , which serve to keep the pawls L' and L^2 in contact with the ratchet-teeth on the edges on the slides E' and I . The pawls L' and L^2 are provided with outwardly and downwardly extending portions M and M' , which are adapted to contact with the cam-surface F' of the coin-lever F , so that when said coin-lever F is depressed said portion F' , through the medium of the extended portions M and M' , will draw the pawls L' and L^2 out of contact with the ratchet-teeth on the edges of the slides E' and I in order that said slides may be free to move downward during such disengagement.

N is a lug attached to the inner face of the pawl L' and is in the path of and adapted to come in contact with the cam-surface O , secured to the inner side of the operating-slide member E' . The spring P is attached to the lower end of the operating-slide E' in such manner that its outer end will contact with the balance-wheel G^4 when the registering-slide I is in its upward or normal position and serves as a brake to prevent the escapement-wheel G from turning when a cent is placed in the receptacle F' until the plunger D is moved downward and withdrawn from the guide portion E of the operating-slide and has allowed said operating-slide to move downward, carrying with it the registering-slide I , and thereby removing the said spring P from contact with said balance-wheel G .

Q and Q' furnish an additional guiding means to the operating-slide E' and the registering-slide I .

The shaft K' extends outward and has attached to its outer end a pointer R , which in conjunction with the dial R' serves to indicate the amount of movement of the registering-slide I . Attached to the shaft K' is a spring S by one of its ends, its other end being attached to the stud S . The spring S serves as a counterbalance for the slide I and to return said slide I to its normal upward position after the operating-slide E' has been returned upwardly by the plunger D .

It is obvious that my improved registering device may be used with various other machines, such as lifting-machines, machines for testing the lungs, and other devices of that class. It can also be used without the coin-operated lever, if desired.

The operation of my improved registering

device is as follows: When used in connection with a weighing-machine, Fig. 1 illustrates the device in its normal position with the platform of the weighing-scale, upward or in a normal position, and the plunger D , the slide E , and the slide I in their normal upward position, where they are held by means of the pawl L' , engaging in the ratchet-teeth E' on the edge of the slide E' , the registering-slide I being held in its upward position by means of the flat elliptical spring S , which is attached to the shaft K' . When a weight is placed upon the platform of the scale, the plunger D is depressed downward and away from the end portion E of the slide E' by means of weight on the platform of the scale, through the medium of the rod T and the bracket T' attached thereto. The rod T is returned to its normal upward position by the spiral spring T' . Then by placing a coin in the coin-receptacle F' the coin-lever F is depressed, and by means of the cam portion F' , acting upon the upwardly-projecting members M and M' , the pawls L' and L^2 are moved out of contact with the slides E' and I , allowing them to drop downward until they again contact with the flange on the plunger D , thus determining the amount of the depression of the scale-platform by the weight or load placed thereon, and in turn registering the weight upon the dial 95 through the pointer R , the shaft K' , pinion K , and the rack J on the slide I . In the meanwhile the lever F , after dropping the cent, is gradually returned to its normal position, as shown in Fig. 1, by means of the counterweight F' ; but its upward movement is retarded by means of the escape-wheel G , escapement G' , and the balance-wheel G^4 a sufficient time to allow the pointer R to come to rest. When said lever F is moved upward to its normal position, it allows the pawl L^2 to move inward and engage with the rack on the edge of the registering-slide I , and thereby lock said registering-slide downward in its registering position until the slide E' has moved upward to its normal position, as shown in Fig. 1. The slide E' in moving upward to its normal position causes the cam portion O to contact with the lug N on the pawl L^2 , release said lug, and thereby allow the slide I to be moved upward to its normal position by means of the elliptical spring S , which in turn causes the pointer R to rotate to a normal or zero position. As the lever F is moved downward by the weight of a coin the pawl F' moves forward upon the ratchet-teeth of the ratchet F^3 a distance equal to the angle of movement of the lever F . The ratchet-pawl F' then engages a tooth and revolves the escapement-wheel G backward a distance equal to the angle of movement of said lever F , and thereby causes the escape-wheel G' to oscillate by means of the teeth on said escapement-wheel G . This furnishes a sufficient retardation to keep the pawls L' and L^2 out of engagement with the

operating-slide and the registering-slide until they have had time to drop downward a distance equal to the depression of the scale-platform and permit the pointer R to register the number of pounds load on the scale.

Registering devices of this class are necessarily delicate in construction, and therefore liable to get out of order and be injured by designing persons, and when operated by a 10 coin it is desirable that they register the weight of but one object at a time—i. e., that they will not register the separate and combined weight of several objects placed on the platform of the scales one after the other.

15 My device is designed to protect the mechanism against injury and fraud, which objects are accomplished in the following manner, to wit: When a load is placed on the platform of the scales, the plunger D is depressed, but 20 the slide E' does not fall downward until a coin has been placed in the receptacle F' and the lever F depressed to release said slide E' and permit it to fall and contact with the plunger D. The slide I is released at the same 25 time and is carried down against the resistance of the spring S a distance equal to the downward movement of the slide E'. Said slide I is locked in its downward position by the pawl L², and at the same time the pawl L' 30 locks the slide E' against further downward movement. The pawls L¹ and L², as has been stated, are controlled by the cam portion F⁶, attached to the coin-operated lever F, and perform their function of locking the slides 35 I and E' when the lever F swings upward through the medium of its counterweight. Said locking-pawls L¹ and L² are moved inward by the springs L³ and L⁴ into contact with the ratchet-teeth E² and I¹, respectively, 40 thus preventing any further downward movement of the slides I and E' by a further depression of the plunger D through additional weight being placed upon the platform. From the foregoing it is seen that the swinging upward of the coin-operated lever F locks 45 both slides, so that one person could not obtain a registration of his weight and another get on the platform and obtain a registration of the additional weight. Furthermore, any 50 accidental jarring of the machine cannot cause rotation of the index and change the registration of the maximum weight upon the platform. Again, should a person desire to injure the registering mechanism by jarring the 55 platform or jumping on it it would cause the plunger D to move up and down and contact with slide E'; but every time such contact was made the slide E' would be moved upward and locked at the highest point of movement of said plunger D, and hence would not 60 again contact at any lesser movement of said plunger. It is obvious that the limited upward movement of the slide E' does not affect the slide I, as the two slides are independent

of each other when the lower end of the portion E' is not in contact with the lug I.

Having now fully described my invention, and the best means of which I am aware for carrying out the same, though without attempting to describe all the forms in which 70 said invention may be embodied, what I claim as my invention, and desire to secure by Letters Patent, is—

1. In a registering mechanism, a coin-controlled releasing-lever; an operating-slide released by said coin-controlled lever; a registering-slide operated by said operating-slide; means for retaining the registering-slide in its normal position; means for retaining the registering-slide in its registering position; and 80 means on the operating-slide for releasing the registering-slide to permit it to return to its normal position.

2. In a coin-operating registering device, co-acting operating and registering slides; means 85 for retaining the operating-slide in its normal position; coin-operated means for releasing the operating-slide; means on the registering slide adapted to engage with the operating-slide; coin-operated means for locking the 90 registering-slide in its registering position; means for returning the operating-slide to its normal position; means on the operating-slide for releasing the registering-slide; and means on said registering-slide to return it to its 95 normal position.

3. In a registering device, a coin-operated lever arranged to be depressed by a coin, contacting therewith; means for retarding the return of said coin-operated lever to its normal upward position; an operating-slide released by the depression of the coin-operated lever, said operating-slide adapted to contact with the registering-slide to move it downward; and means controlled by the coin-lever 105 for locking said registering-slide in a registering position; means for unlocking said registering-slide, and for moving it to its normal position.

4. In a registering device, an operating-slide 110 and coin-operated means for releasing said operating-slide; a registering-slide arranged to be moved to a registering position by the operating-slide, said registering-slide being independent of the operating-slide when same 115 is being moved upward to its normal position; means on the operating-slide arranged to release the registering-slide when said operating-slide has moved upward to its normal position; and a spring to return said registering-slide to its normal position.

5. In a registering device having co-operating operating and registering slides; means for releasing the operating-slide; means on the registering-slide adapted to contact with the operating-slide, whereby said registering-slide is moved downward; registering means actuated by the registering-slide; and means

for returning the operating-slide to its normal position.

6. In a registering device, an operating-slide; coin-controlled means for releasing the operating-slide; a registering-slide moved downward by said operating-slide; registering means actuated by said registering-slide; independent means for locking the registering-slide; and retracting means for returning the registering-slide to its normal or inoperative position.

7. In a registering device, a coin-operated lever; an operating-slide released thereby; a co-operating registering-slide; and independent means to lock said registering-slide in a registering position.

8. In a registering device, a coin-operated lever; means for controlling the return speed of said lever; an operating-slide released by said coin-operated lever; a registering-slide moved downward by said operating-slide; and means for preventing further downward movement of said operating-slide, and for preventing upward movement of the registering-slide, both said means being independent of each other.

9. In a registering device, a coin-operated lever; means for controlling the return speed of said coin-operated lever; an operating-slide released by said coin-operated lever; a registering-slide moved downward by said operating-slide; registering means operated by said registering-slide; means to lock the operating-slide against downward movement, and for locking the registering-slide against upward movement controlled by the coin-operated lever and retracting means for returning said operating and registering slide to their normal positions.

10. In a registering device, a coin-operated lever; means for controlling the return speed

of said coin-operated lever; locking means operated thereby to lock and release an operating-slide; said operating-slide; registering means moved to a registering position by said operating-slide, but independent thereof, 45 when the weight of a given thing has been registered; means to lock said registering device in a registering position; means on the operating-slide to unlock said registering means; and means to return it to its normal 50 or zero position.

11. In a registering device, a coin-operated lever; an operating-slide adapted to be locked when in a normal position; means to unlock said operating-slide by the movement of the 55 coin-operated lever; registering means operated by said operating-slide; means for locking said registering means in a registering position independent of the operating-slide; means on said operating-slide for unlocking 60 said registering means; and independent retracting means for returning it to its normal position.

12. In a registering means, a coin-operated lever; an operating-slide; a registering-slide 65 moved downward by said operating-slide; means operated by the coin-operated lever for locking the registering-slide in its registered position; and means for retaining said registering-slide in its normal position until said 70 operating-slide has partially returned to its normal position.

In testimony whereof I have hereunto set my hand, in the presence of two subscribing witnesses, this 21st day of October, 1902.

JOHN G. W. ROMANS.
